UNITED STATES PATENT OFFICE.

WILLIAM ROSS, OF CHICAGO, ILLINOIS.

FUEL-CONTROLLING MECHANISM FOR ENGINES.

1,210,005.

Specification of Letters Patent. Patented Dec. 26, 1916.

Application filed June 1, 1916. Serial No. 101,124.

To all whom it may concern:

Be it known that I, WILLIAM Ross, a citizen of the United States, residing at Chicago, in the county of Cook and State of Illinois, have invented a new and useful 5 Fuel-Controlling Mechanism for Engines, of which the following is a specification.

The present invention is a fuel controlling mechanism for internal combustion engines, 10 and aims to provide a novel and improved means for supplying the gasoline or other liquid fuel to the carbureter or fuel atomizing device, whereby predetermined charges of fuel are delivered to the carbureter as the engine operates, to furnish the 15 engine with the necessary fuel, without there being an over supply.

The present invention also aims to eliminate the use of float controlled valves in carbureters, and similar contrivances now used, 20 which easily get out of order, so as to disturb or impair the efficient operation of the engine.

With the present mechanism, the carbureter can be of very simple construction, 25 using no float controlled valve to control the supply of gasoline, and the mechanism embodies a minimum number of parts.

It is also the object of the invention to 30 provide fuel supplying means operated in synchronism with the crank shaft of the engine, whereby the amount of fuel delivered to the carbureter is proportional with the speed of the engine, in order to furnish each 35 cylinder with a predetermined amount of fuel in the air sucked into the cylinder, whereby a most efficient operation of the engine is obtained.

A further object of the invention is the 40 provision of means whereby the charges of fuel delivered to the carbureter can be increased or decreased, to change the proportion of gasoline or other fuel under various conditions.

With the foregoing and other objects in view which will appear as the description proceeds, the invention resides in the combination and arrangement of parts and in the details of construction hereinafter described 45 and claimed, it being understood that changes in the precise embodiment of the invention herein disclosed can be made within the scope of what is claimed without departing from the spirit of the invention.

The invention is illustrated in the accompanying drawings, wherein:—

Figure 1 is a side elevation of an engine equipped with the present fuel controlling mechanism, the carbureter and valve structure being shown in section. Fig. 2 is a 60 plan view of the engine and present mechanism. Fig. 3 is an enlarged sectional detail of the valve mechanism taken on the line 3—3 of Fig. 2.

In the drawings, there is illustrated a carbureter 1, which is to be taken as typical, 65 since various suitable carbureters can be used with the present mechanism. The carbureter illustrated embodies an air suction casing 2 attached to the intake manifold 3 70 of the engine and through which the air is sucked from the atmosphere to the cylinders, said casing 2 having a contracted portion 4 and a fuel conducting tube 5 terminating in nozzle 6 within the reduced portion 4, whereby 75 the air in being drawn through the portion 4 past the nozzle 6 will atomize the fuel to provide the proper combustible mixture. The carbureter is provided with a fuel cup 7 with which the tube 5 is integral, said cup 80 and tube 5 providing a funnel, of which the tube 5 is the spout to convey the fuel from the cup or body 7 to the nozzle 6 by gravity. A cap or plug 8 is threaded into or otherwise engaged with the mouth portion of the 85 cup 7, and said cup is provided adjacent its upper end with an air vent 9 of restricted area.

A valve is provided to deliver the fuel in 90 charges of predetermined volume into the cup 7, and as illustrated, said valve embodies a casing 10 integral with the cap 8 of the cup 7, and provided with a tapered transverse bore 11, a lower port 12 extending from said bore and communicating with the 95 cup 7 and an upper port 13 extending outwardly from the bore 11. A fuel supply pipe or tube 14 has its lower end attached to the upper end of the casing 10 in any suitable manner, and has its upper end connected to a fuel tank or reservoir 15, which is 100 elevated in order that the fuel will feed by gravity to the valve. This tank 15 may be the main fuel tank, or a supplemental or secondary tank to which the fuel is 105 pumped, sucked or otherwise fed from the main tank which may be at a lower level, as at the rear end of the automobile. The valve

member is in the form of a tapered plug or spigot 16 rotatable within the bore 11, and provided at its smaller end with a stem 17 upon which a washer 18 is fitted, said washer bearing against the casing 10 and being held in place by a nut 19 threaded upon the stem 17, whereby when said nut is tightened, the plug 16 will be seated snugly within the bore 11 to prevent leakage. The plug 16 is provided with a radial pocket or recess 20 of predetermined size, to hold a given volume of fuel. The larger end of the plug 16 has an outstanding tubular stem 21, the bore 22 of which extends axially into the plug 16 to the pocket 20. This plug 16 is rotated in synchronism with the crank shaft of the engine, whereby the fuel supplied to the carbureter is proportional to the speed of the engine. The plug 16 is therefore operatively connected with the crank shaft or other rotatable part of or operated by the engine, and various connections can be used for this purpose. The operative connection illustrated embodies a bevel gear 23 secured upon the tubular stem 21, and meshing with a bevel gear 24 secured upon the end of a longitudinal shaft 25 disposed at one side of the engine and journaled adjacent the bevel gear 24 in the bearing 26 of a bracket 27 which as illustrated is integral with the valve casing 10. The shaft 25 is journaled adjacent its other end in a bearing or bracket 28 attached to the crank case of the engine or other suitable support, and a sprocket wheel 29 is attached to this end of the shaft 25 and is connected by an endless sprocket chain 30 with a sprocket wheel 31 secured upon the crank shaft 32 of the engine or other part rotated by the engine. Any suitable connection, however, between the valve and engine can be used, whereby the plug 16 is operated in synchronism with the engine, the valve plug 16 making a revolution for every explosion, or if the plug 16 is provided with a plurality of pockets 20, the plug 16 is rotated one step for each explosion.

As a means for changing the proportion of fuel, a plunger 33 is slidable in the tubular stem 21 and extends through the bore 22 into the pocket 20, whereby when said plunger is projected into the pocket 20, the pocket will hold less fuel, and when the plunger 33 is retracted, the pocket can hold its full volume of fuel, whereby the adjustment of the plunger will regulate the charges of fuel supplied to the carbureter. The plunger 33 can be controlled manually in any suitable manner, and as a convenient means of accomplishing this, the plunger 33 is provided adjacent its outer end with a grooved collar 34 engaged by one arm of a bell crank lever 35 having its elbow pivoted to an outstanding arm 36 carried by the bearing 26, and a rod 37 is connected to the other arm of the bell crank lever 35 and

can extend to the dash board or other suitable point of the automobile, and can be operated by a lever, handle or other manually controlled member.

When the engine is at a standstill, the plug 16 will remain stationary, thus cutting off communication between the carbureter and tank 15, whereby there is no possible flow of the fuel to and out of the carbureter. When the engine is in operation, the crank shaft 32 being rotated, will transmit motion to the plug 16, whereby the pocket 20 thereof is alternately brought into register with the ports 12 and 13, the plug operating in synchronism with the crank shaft to provide for the intermittent supply of fuel to the carbureter in step with the explosions. When the pocket 20 registers with the port 13, the pocket will be filled with liquid from the supply pipe 14, the air bubbles passing from the pocket up the pipe 14 to the tank 15, and then when the plug 16 is turned over, so that the pocket 20 registers with the port 12, the contents of the pocket will flow through the port 12 into the cup 7, air being admitted through the air vent 9 and passing through the port 12 into the pocket 20. The fuel which is discharged into the cup 7 will flow through the tube 5 to the nozzle 6, and will be atomized by the air suction. It is preferable to so time the plug 16, that the charge of fuel is delivered into the cup 7 and to the nozzle 6 at the beginning of or during the intake stroke of the respective cylinder, whereby the current of air flowing through the carbureter will suck the charge of fuel from the carbureter into the cylinder. Thus, during the intake strokes of the pistons, the charges of predetermined volume are delivered to the carbureter to be carried off by the air suction, and in this way, each cylinder is supplied with a predetermined quantity of fuel. The faster the engine operates, the faster the plug 16 rotates, so that the same quantity of fuel is consumed by each explosion, at any speed of the engine. The engine can be throttled by means of the throttle valve 38 within the upper portion of the carbureter casing 2, as usual, and the proportion of fuel used can be controlled by operating the plunger 33, which can be moved either inwardly or outwardly, to decrease or increase the proportion of fuel consumed. The plunger 33 can rotate with the plug 16, and it is preferable to provide a packing gland 39 upon the end of the stem 21 to prevent leakage along the plunger 33.

The present mechanism provides for a regulated supply of fuel to the engine, such as is not possible with the use of ordinary carbureters, and with the present mechanism, a carbureter of very simple construction can be used, eliminating the float controlled valve and kindred devices which

easily get out of order. This invention reduces to a minimum the wastage of fuel, and has other obvious advantages.

Having thus described the invention, 5 what is claimed as new is:

1. A fuel supplying mechanism for an internal combustion engine, embodying an air suction passage, a fuel cup having an air vent, a fuel nozzle communicating with 10 the bottom of said cup and projecting within said passage for conducting the fuel from the cup by gravity into said passage, the fuel being atomized within said passage, means for conducting fuel into said cup, and means 15 adapted to be operated by an engine for controlling the flow of fuel into the cup so that the fuel is delivered into the cup intermittently.
2. A fuel supplying mechanism for an in-

ternal combustion engine, embodying an air 20 suction passage, a funnel-shaped fuel cup having an air vent, the spout of said cup terminating in a nozzle in said passage whereby the fuel flows by gravity from the cup to said nozzle to be atomized within said 25 passage, a cap for said cup having a valve casing, means for supplying fuel through the valve casing to the cup, and a valve movable within the valve casing for delivering the fuel intermittently into the cup. 30

In testimony that I claim the foregoing as my own, I have hereto affixed my signature in the presence of two witnesses.

WILLIAM ROSS.
